Primary Examiner — Janice Hallmark(74) *Attorney, Agent, or Firm* — Thomas A. O'Rourke; Bodner + O'Rourke, LLP(57) **CLAIM**

The ornamental design for a spike stick, as shown and described.

DESCRIPTION

FIG. 1 is a perspective view of the spike stick of the present invention.

FIG. 2 is a top view of the spike stick of FIG. 1.

FIG. 3 is a front view of the spike stick of FIG. 1. The rear view is identical to the front view shown.

FIG. 4 is a bottom view of the spike stick of FIG. 1.

FIG. 5 is a right side view of the spike stick of FIG. 1. The left side is identical to the right side shown.

FIG. 6 is a perspective view of an alternative embodiment of the spike stick of the present invention.

FIG. 7 is a top view of the spike stick of FIG. 6.

FIG. 8 is a front view of the spike stick of FIG. 6. The rear view is identical to the front view shown.

FIG. 9 is a bottom view of the spike stick of FIG. 6.

FIG. 10 is a right side view of the spike stick of FIG. 6. The left side is identical to the right side shown.

FIG. 11 is a perspective view of an alternative embodiment of the spike stick of the present invention.

FIG. 12 is a top view of the spike stick of FIG. 11.

FIG. 13 is a front view of the spike stick of FIG. 11. The rear view is identical to the front view shown.

FIG. 14 is a bottom view of the spike stick of FIG. 11; and, FIG. 15 is a right side view of the spike stick of FIG. 11. The left side is identical to the right side shown.
